UNITED STATES PATENT OFFICE

WALDEMAR PETERSEN, OF DARMSTADT, GERMANY

REGULATING TRANSFORMER

Application filed October 2, 1926, Serial No. 139,126, and in Germany September 23, 1925.

This invention relates to regulating transformers and has for its object to provide an improved apparatus of this character.

The variation of the transformation ratio 5 of a transformer by means of tappings or an auxiliary transformer, as has previously been proposed, necessitates the employment of expensive and complicated switching apparatus in cases in which the variation is 10 effected under voltage or load.

The subject-matter of the present invention avoids this disadvantage by enabling the variation of the transformation ratio of a transformer to be effected in such a manner that by the provision of at least two parallel magnetic circuits within one and the same primary winding and of regulating windings suitably distributed and coupled to control the flux distribution to the said 20 magnetic circuits as desired so that variable voltages are induced in the secondary windings. The regulating operation is thus transferred from the primary or secondary windings to the particular regulating windings provided therefor, this arrangement having the great advantage that only low 25 voltages or small currents require to be controlled, as the number of turns of the regulating windings and therefore the voltages induced therein may be chosen independently of those of either the primary or secondary windings.

The invention is illustrated in the accompanying diagrammatic drawings which 35 show, by way of example, a number of different arrangements embodying the invention.

Figure 1 shows one leg portion of a single or polyphase transformer in cross section;

Figure 2 is a side elevation thereof;

40 Figures 3, 4 and 5 show also by side elevation one leg portion of three different transformer constructions;

Figure 6 gives a diagrammatic reproduction 45 of a transformer with a controlling device for the regulating windings.

In the transformer construction shown in Figure 1, which represents only one leg portion of the transformer, the core of the represented leg portion of the transformer is subdivided into two core sections a_1 and a_2 . The primary winding, which surrounds both core sections, is indicated at c , while the spools of the secondary winding are indicated at d_1 , d_2 , and the regulating windings at f_1 , f_2 .

The two halves of the secondary winding d_1 and d_2 are oppositely connected, and the two regulating windings f_1 and f_2 can be coupled in normal series connection or so connected in series that the corresponding electromotive forces are of respectively opposite directions, as indicated in the drawing.

For a constant voltage impressed on the primary winding c the total flux N traversing the core sections is constant. This flux divides into two flux portions N_1 and N_2 traversing the core sections a_1 and a_2 respectively in the inverse ratio of the number of turns s_{31} and s_{32} of the regulating windings f_1 and f_2 .

$$N_1 : N_2 = s_{32} : s_{31} \quad \dots \quad (1)$$

as a result, since $N_1 + N_2 = N$,

$$N_1 = N \frac{s_{32}}{s_{31} + s_{32}} \quad \dots \quad (2)$$

$$N_2 = N \frac{s_{31}}{s_{31} + s_{32}} \quad \dots \quad (3)$$

The voltage induced by the total flux N in the number of turns s_{22} of the secondary winding d_2 of the core a_2 will be denoted by

$$E = kNs_{22} = \text{constant} \quad \dots \quad (4)$$

similarly the voltage induced by the flux portion N_1 in the secondary winding d_1 having a number of turns s_{21} will be denoted by

$$E_{21} = kN_1 s_{21}$$

and, similarly, the voltage induced by the flux portion N_2 in the secondary winding

90

d_2 having a number of turns s_{22} will be denoted by

$$E_{22} = kN_2 s_{22}$$

By reference to Equations 2 and 3, I obtain:

$$E_{21} = E \frac{s_{32}}{s_{31} + s_{32}} \cdot \frac{s_{21}}{s_{22}} \quad \dots \dots \dots \quad (5)$$

$$E_{22} = E \frac{s_{31}}{s_{31} + s_{32}} \quad \dots \dots \dots \quad (6)$$

with opposing connection of d_1 and d_2 it will be apparent that the secondary voltage

$$E_2 = E_{22} - E_{21}$$

$$E_2 = E \frac{s_{31} - s_{32} \cdot \frac{s_{21}}{s_{22}}}{s_{31} + s_{32}} \quad \dots \dots \dots \quad (7)$$

In the case in which the numbers of turns of the two secondary winding sections are equal to one another, that is to say

$$s_{21} = s_{22}$$

Equation 7 will take the following form

$$E_2 = E \frac{s_{31} - s_{32}}{s_{31} + s_{32}} \quad \dots \dots \dots \quad (8)$$

The large range of regulation expressed by Equation 7 may be further increased, if the two regulating windings, instead of being directly coupled together are coupled through an ordinary transformer, or an auto-transformer having a variable transformation ratio. This transformation ratio may be defined by the equation.

$$E_{32} = aE_{31}$$

in which E_{32} is the voltage of the side of the intermediate transformer connected to f_2 and E_{31} is the voltage of the side of the intermediate transformer connected to f_1 . The factor a can have a positive or negative value, as desired.

A further constructional example is shown in Figure 2. In this figure the secondary winding section d_1 is omitted; as regards the remaining elements the core sections a_1 and a_2 , the primary winding c and the regulating windings f_1 and f_2 are the same as in Figure 1, b being the yoke of a single or polyphase transformer.

The operation of regulation is the same as before, the total flux N remaining constant and being distributed by means of the regulating windings in any desired ratio between the two core sections a_1 and a_2 .

Equation 8 of the simplified switching corresponds to

$$E_2 = E \frac{s_{31}}{s_{31} + s_{32}} \quad \dots \dots \dots \quad (9)$$

In the further constructional examples shown in Figures 3 and 4, the core is constructed as before, with at least two core sec-

tions, a_1 and a_2 in Figure 3, a_1 , a_2 , a_3 in Figure 4, which are connected by means of magnetic bridges h_1 , h_2 . . . etc. In the simple example shown in Figure 3 the core section a_2 only carries the coils d_1 , d_2 , d_3 . . . etc. of the 70 secondary winding. The regulating windings are indicated at f_1 and f_2 , g_1 and g_2 and l_1 and l_2 . The primary winding is indicated at c and the yoke at b .

In this construction the flux, which has an 75 inducing action on the secondary winding can be varied in each coil section quite independently of the other coil sections. If, for example, f_2 (g_2 , l_2 . . .) is short-circuited, and f_1 (g_1 , l_1 . . .) is open-circuited, the 80 effective flux will exclusively traverse the core section a_1 .

By a parallel connection of f_1 and f_2 and by varying the number of turns of f_1 and f_2 and flux can, as in the case of Figures 1 and 2, be 85 transferred to the upper part of the core section a_2 . By short-circuiting f_1 and open-circuiting f_2 , the total effective flux will traverse the winding d_1 (Figure 3) and will pass through the bridge h_1 as indicated in 90 Figure 3. In a manner readily understood the flux traversing the windings d_2 and d_3 can be transferred or deviated in any desired stages from a_1 to a_2 .

In the further constructional example of 95 Figure 5, b , b are the yokes of a single or polyphase transformer, a_1 , a_2 the core sections of the transformer leg, h a connecting bridge between the two core sections, c the primary winding of the leg, d a secondary winding 100 located on the connecting bridge h , and e , f , i and k are the regulating windings.

In the low voltage condition of the secondary winding d the regulating windings e and f as also the winding i and k having equal 105 numbers of turns, are connected in parallel with one another. The effective flux traverses the core sections a_1 and a_2 , the bridge h being not traversed by flux. If it is desired that d should be inductively influenced to the full 110 extent by the effective flux, e and k must be short-circuited, and f and i connected in parallel with one another. The flux takes the path through f across h and through i . If, on the other hand, f and i are short-circuited 115 and e and k are connected in parallel with one another, the flux will pass through h in the opposite direction to that given above.

The substantially continuous or graduated adjustment of the voltage on the winding d 120 will evidently take place as in the constructional examples of Figures 1 or 2. The regulating windings e and k on the one hand, and f and i on the other hand, have corresponding characteristics, so that, for this reason, e and k on the one hand, and f and i on the other hand, can be connected in circuit to one 125 winding corresponding to f_1 and f_2 in Figures 1 and 2. In the utilization of the inventive idea in a reactance coil, which is a light- 130

ly loaded transformer without a secondary winding, the secondary windings d_1 and d_2 are dispensed with, for instance, in the constructional form of Figures 1 and 2.

The core sections a_1 , a_2 . . . can be constructed so as to have different magnetic reluctances.

If, for instance, a_1 has a low magnetic reluctance, whilst a_2 has a high magnetic reluctance, the primary winding will constitute a small reactance when the regulating winding has deviated the flux to a_1 . When, on the contrary, the flux is deviated to a_2 by the regulating winding, the primary winding will increase in reactance.

In order to show how the regulating windings may be controlled, a control device is represented in Figure 6 for regulating the connections of these windings. In this figure the movable element M which as shown is divided into three conducting sections separated by insulated parts may be moved over a series of contacts to change the connections of the regulating windings. This figure shows a simple conventional switching arrangement whereby the regulating windings may be connected in parallel or in series and also whereby either winding f_1 or f_2 may be open circuited while the other is short circuited. It is apparent that additional contacts and connections may be employed to change the number of turns in either of these windings to vary the regulating effect. Any convenient mechanism may be employed to move the element M over the contacts in either direction to bring about the desired connections.

As in all transformers, the foregoing conditions are reversible, the primary and secondary windings being interchangeable. Furthermore the improved transformer can serve, for example, to effect transformation from constant current in the windings d_1 and d_2 to constant voltage in the winding c .

5 What I claim is:—

1. A regulating transformer comprising a magnetic core subdivided into a plurality of core sections, a primary winding with its turns extending around all of said core sections, a secondary winding having its turns on parts thereof and independent regulating windings inductively related to said core sections, arranged to be excited by said primary winding and controlling means to connect said regulating windings in regulable manner with respect to each other and to said core sections so as to allow a variation of the magnetic flux distribution with respect to the secondary winding.

10 2. A regulating transformer comprising a magnetic core subdivided into a plurality of core sections, at least one magnetic connection bridge between said core sections, a primary winding with its turns extending around all of said core sections, a secondary

winding having its turns on parts thereof and independent regulating windings inductively related to said core sections, arranged to be excited by said primary winding and controlling means to connect said regulating windings in regulable manner with respect to each other and to said core sections and connection bridge so as to allow a variation of the magnetic flux distribution with respect to the secondary winding.

75 3. A regulating transformer comprising a magnetic core subdivided into a plurality of core sections, said core sections being constructed with different magnetic reluctance, a primary winding with its turns extending around all of said core sections, a secondary winding having its turns on parts thereof and independent regulating windings inductively related to said core sections, arranged to be excited by said primary winding and controlling means to connect said regulating windings in regulable manner with respect to each other and to said core sections so as to allow a variation of the magnetic flux distribution with respect to the secondary winding.

In witness whereof I have hereunto signed my name this 17th day of September, 1926.
